[57] CLAIM

The ornamental design for a electroluminescent transparency illuminator, as shown.

DESCRIPTION

FIG. 1 is a front perspective view of the electroluminescent transparency illuminator of the present invention; FIG. 2 is a side view in elevation of the electroluminescent transparency illuminator of FIG. 1 as seen from the right-hand side of FIG. 1;

FIG. 3 is a side view in elevation of the electroluminescent transparency illuminator of FIG. 1 as seen from the left-hand side of FIG. 1;

FIG. 4 is a front view in elevation of the electroluminescent transparency illuminator of FIG. 1;

FIG. 5 is a bottom plan view of the electroluminescent transparency illuminator of FIG. 1;

FIG. 6 is a top plan view of the electroluminescent transparency illuminator of FIG. 1; and,

FIG. 7 is a rear view in elevation of the electroluminescent transparency illuminator of FIG. 1.

FIG. 1

FIG. 2

FIG. 3

FIG. 4

FIG. 5

FIG. 6

FIG. 7
